UNITED STATES PATENT OFFICE.

JAMES W. URIE, OF CARSON CITY, MICHIGAN, ASSIGNOR OF ONE-HALF TO A. B. GOODWIN, OF CARSON CITY, MICHIGAN.

WIRE-TWISTER.

1,377,373.

Specification of Letters Patent. Patented May 10, 1921.

Application filed April 14, 1920. Serial No. 373,815.

To all whom it may concern:

Be it known that I, JAMES W. URIE, citizen of the United States, residing at Carson City, county of Montcalm, and State 5 of Michigan, have invented new and useful Improvements in Wire-Twisters, of which the following is a specification.

This invention relates to tools, particularly to wire twisting devices for applying 10 wire to bales and the like, and has for its object the provision of a novel wire twisting device adapted for use in the chuck of an ordinary breast drill and which includes means for clamping the ends of a wire tight 15 and which further includes means for cutting the wire after a twist has been made therein.

An important object is the provision of a device of this character which is provided 20 with a removable member interposed in the end portion which will assist in the proper twisting of wires of different sizes, a plurality of these members being provided, all of which are interchangeable.

25 An additional object is the provision of a device of this character which will be simple and inexpensive in manufacture, easy and efficient in use, durable in service, and a general improvement in the art.

30 With the above and other objects and advantages in view, the invention consists in the details of construction to be hereinafter more fully described and claimed, and illustrated in the accompanying drawings in 35 which—

Figure 1 is an elevation of my device, showing it associated with a breast drill,

Fig. 2 is an enlarged side elevation of my device detached,

40 Fig. 3 is a longitudinal sectional view, Fig. 4 is an elevation taken at right angles to Fig. 2,

Fig. 5 is an elevation of the opposite side,

45 Fig. 6 is a cross sectional view taken on the line 6—6 of Fig. 4, and

Fig. 7 is a detail view of one of the removable nostril members.

Referring more particularly to the drawings, the numeral 10 designates the body 50 which is reduced at one end to form a shank 11 engageable within the chuck A of a breast drill B. At its other end the body 10 is formed with a lateral notch or recess 13 and has its extremity formed with a central hole 12.

Formed upon one side of the body 10 are spaced ears 14 between which is pivoted, as at 15, a cutting member including a bar 16 carrying at its end a pivoted blade 17 adapted to enter and fill the recess or notch 60 13. The edge of this blade is of course sharpened so as to have a cutting action. I also provide a spring 18 located between the ears 14 and normally urging the bar 16 in such a direction that the blade will be 65 in non-cutting position. Also pivoted between the ears 14 is a lever 19 having one end formed as a handle diverging from the body 10 and having its other end engaging beneath the free end of the bar 16. When 70 the operator grasps the device and squeezes the lever 19 toward the body the blade 17 will enter the notch or recess 13.

Formed in the body 10 at the side opposite the ears 14, is a recess 20 which communicates by a hole 21 with the central hole 12. Pivoted within this recess 20, as shown at 22, is a lever 23 having a cam head 24 acting as a clamp for engaging and holding wires inserted within the device and extending along the recess 20.

75 Removably disposed within the hole 12 is a nostril member 25 which has a bore with a flaring entrance end 26. This nostril member is held in position by a suitable set-screw 80 28 passing through one side of the body. If preferred, the flaring end of this bore 26 may be provided with oppositely arranged shoulders 27.

85 The use of the device is as follows:

Assuming that a length of wire is passed 90 about a bale, box, or other article which it is desired to secure, the ends of this wire are passed through the bore of the nostril member 25 and are passed through the hole 21 95 and extended along the recess 20. The operator then squeezes the cam lever 23 against the body whereupon the cam head 24 thereof will clampingly engage the wires within the recess 20. The operator then rotates the operating wheel or handle of the drill and this results in rotation of the entire device and this will of course cause a twisting together 100 of the ends of the wire. After the twist is made the operator presses upon the lever 19 105 which will force the cutting blade 17 into the notch or recess 13 and effect severing of the wire. The ends cut off will then drop out of the recess 20 when the lever 23 is moved outwardly.

It will be observed that when different sizes of wire are to be used that there would be a plurality of the nostril members 25, all having bores of different diameters so that 5 the different sizes of wires may be accommodated. In the event that the nostril member used is provided with the shoulders 27, it will be seen that these shoulders will engage against the wires and assist in making 10 a proper twist.

From the foregoing description and a study of the drawings it will be apparent that I have thus provided a simply constructed and easily operated wire twisting 15 device which is provided with efficient clamping means and which has a novelly arranged cutting mechanism in addition to the interchangeable guide or nostril members for accommodating different sizes of 20 wires. It will be apparent that in actual practice it will be unnecessary to make very many twists and it will consequently be seen that probably a single rotation of the drill handle will be sufficient. Owing to these 25 facts it will be seen that the device may be used with considerable speed and that the wire twisting operation will involve but little effort and be a material time saver.

While I have shown and described the 30 preferred embodiment of my invention, it is of course to be understood that I reserve the right to make such changes in the form, construction, and arrangement of parts as will not depart from the spirit of the invention 35 or the scope of the subjoined claims.

Having thus described my invention, I claim:

1. A device of the character described comprising a body formed at one end for engagement within a drill chuck, said body being provided at its other end with a circular hole and a transverse recess intersecting the hole, said body being formed in one side with a longitudinal recess communicating

with said hole, a lever pivoted within said 45 longitudinal recess and having a cam head co-operating with the bottom of the longitudinal recess whereby to serve as a clamp, a movable cutting blade extending into said transverse recess, and a lever pivoted at one 50 side of the body and connected with said blade.

2. A device of the character described comprising an elongated body provided in one end with a circular hole and formed 55 with a lateral recess intersecting the hole, the body being further provided on one side with a longitudinal recess into which said hole leads, clamping means within said longitudinal recess, cutting mechanism extending into said transverse recess, the other end of the body being provided with a counterbore, a removable nostril member disposed within the counterbore and having a bore with a flaring entrance end, and a set screw 60 for holding said nostril member in position.

3. A device of the character described comprising an elongated body adapted for engagement within a drill chuck and provided at one end with a central hole, the 70 body having a V-shaped transverse recess intersecting said hole and being also provided with a longitudinal recess into which said hole leads, wire clamping means within said longitudinal recess, and cutting mechanism 75 including a bar pivoted on the side of said body opposite the longitudinal recess, a blade pivotally connected with said bar and operating within said transverse recess, a spring engaging said bar for normally holding the blade in inoperative position, and a pivoted lever having one end formed as a handle and its other end engaging the free end of said bar.

In testimony whereof I hereto affix my 85 signature.

JAMES W. URIE.
